UNITED STATES PATENT OFFICE

WILLIAM C. HIERING, OF NEWARK, NEW JERSEY, ASSIGNOR TO J. E. MEROOTT COMPANY, OF NEWARK, NEW JERSEY, A CORPORATION OF DELAWARE

HAND BAG

Application filed June 18, 1932. Serial No. 617,981.

This invention relates to handbags, and more particularly to handbag frames and means for attaching covering material to such frames.

5 Handbags are extensively manufactured with metal frames to which the covering material, such as leather or cloth is attached. In many instances the covering material is sewed to the frame, but in order to facilitate 10 the manufacture and improve the appearance of bags, it is desirable to attach the covering material to the frame by means other than sewing.

Heretofore, I have provided a handbag 15 frame of channel shape for receiving and securely holding a metal insert, preferably of channel shape, to which bag covering material is attached by means other than sewing. While such a method has proven desirable and satisfactory, it has been found that 20 from a manufacturing standpoint, considerable time is consumed in preventing bunching of the bag material at corners, and that the process of attaching covering material 25 to a frame may be simplified by my invention as herein described, and at the same time present a finished bag having a neater outer appearance than has heretofore been possible with frame structures commonly 30 used.

It is, therefore, an object of this invention 35 to provide a channelled frame for handbags, the frame being of substantially U-shape and having permanently attached to its legs or parallel side members, channelled inserts opening inwardly towards each other, the covering material being clamped between the channelled inserts after it has been attached to the longitudinal portion of the 40 U-shaped frame member.

A further object is the provision of a frame member for handbags having means by which bag covering material may be attached thereto without causing bunching at 45 the corners, and at the same time present a

finished bag having a neat outer appearance.

These and other advantageous objects which will later appear, are accomplished by the simple and practical construction and arrangement of parts hereinafter described 50 and exhibited in the accompanying drawing, forming part hereof, and in which:

Fig. 1 is a perspective view, partially in section, of a handbag embodying my invention, 55

Fig. 2 is an exploded view of the frame member,

Fig. 3 is a sectional view, taken in perspective on line 3—3 of Fig. 1,

Fig. 4 is a sectional view of a modified 60 form, and

Fig. 5 is another modification.

Referring to the drawing, my improved bag frame is shown to include two similar, 65 hingedly connected frame members 1 and 2, each member being made from a suitable blank of material bent to present, in cross section, an outwardly disposed channel, comprising a relatively long inner side wall 15 provided with top and bottom flanges 70 14 and 16 directed outwardly at right angles thereto, the bottom flange 16 being provided with a plurality of spaced tangs 18, having apertures 19 to enable the tangs 75 to be readily bent upwardly, parallel with the inner side wall 15, for a purpose to be presently explained.

The frame has generally the shape of an inverted U, that is, a main longitudinal section A, with right angularly directed legs 80 B.

In each leg B of the frame member, there is positioned a channelled insert opening inwardly, (see Fig. 2). The tangs are bent 85 parallel with the inner side wall 15 to grip the lower wall 22 of the inserts to securely hold them in place.

The lower walls 22 of the channelled inserts in the legs B, are provided with a pair of spaced protuberances 31 which co- 90

operate with the tangs 18 on the legs to position the channelled inserts definitely in the legs B of the frame member, so that an extension 32 on the upper wall 23 will lie in the main longitudinal section A, in line with the channelled insert 21.

In the preferred form of my invention, the bag covering material 20, which may be leather, cloth or the like, is laid out in a flat position, and the longitudinal edge thereof is inserted in a channelled insert 21, the latter being then crimped to securely hold the covering material therein. The channelled insert 21, with the bag covering material secured thereto, is then inserted in the main section A, of the frame member, between the top and bottom flanges 14 and 16, and the perforated tangs 18 are then bent upwardly to hold the insert in the frame member as shown in Fig. 3, with the channel opening outwardly. It is to be understood that the structure of both frame members 1 and 2 is the same.

After the channelled insert 21, with the covering material 20, has been secured to the longitudinal section A of the frame member, the side edges of the covering material are inserted in the channelled inserts in the legs B, after which the upper walls 23 of the inserts are pressed down to clamp the covering material between walls 22 and 23 of the inserts.

By means of the structure above described, covering material can be readily attached to the frame member, and there is no bunching of the material at the corners. After the material is attached to the frame members as above described, it is folded to present a bag having the neat appearance, as shown in Fig. 1; it being noted that the folded material effectively conceals the inserts in the legs B, of the frame members.

In a slightly modified form of the invention, (see Fig. 4), the channelled insert 21 may be provided with slots 30, through which are passed the tangs 18 on the section A of the frame member. The tangs are then bent upwardly to securely hold the insert 21 in the frame member.

In Fig. 5 is shown a modified form in which the insert 40 in the longitudinal section, and the inserts 41 in the legs, have their adjacent ends mitered, this form also enabling bag covering material to be neatly secured to the frame members without bunching at the corners.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what

I claim as new and desire to secure by Letters Patent, is:

1. In a handbag, a channelled U-shaped frame member, the channel of the frame member opening outwardly and laterally relative to the bag, channelled inserts attached to the legs of the frame member and opening inwardly, a channelled insert opening outwardly and positioned in the longitudinal main section of the frame member, and means on the frame member for clamping the last mentioned insert in position. 70

2. In a handbag, a channelled frame member having a main section and right angularly directed legs to present substantially the shape of an inverted U, the channel of the frame member opening outwardly and laterally relative to the bag, inwardly opening channelled inserts positioned in the legs of the frame member, means on the frame member to engage the lower walls of said inserts to hold them securely in position, an outwardly opening channelled insert positioned in the main section of the frame, and means on the frame to clamp the last mentioned insert in position. 80

3. In a handbag, a channelled frame member having a main section and right angularly directed legs to present substantially the shape of an inverted U, the channel of the frame member opening outwardly and laterally relative to the bag, a channelled insert having covering material clamped therein, said insert being positioned in the longitudinal main section of the frame member and opening outwardly, means on the frame member to securely hold the insert in position, inwardly opening channelled inserts positioned in the legs of the frame member, and means on the frame member engaging the lower walls of said inwardly opening inserts to hold them securely in position, the upper walls of said inserts being adapted to be pressed downwardly to tightly grip the side edges of the covering material. 95

4. In a handbag, a channelled frame member having a main section and right angularly directed legs to present substantially the shape of an inverted U, the channel of the frame member opening outwardly and laterally relative to the bag, a channelled insert having covering material clamped therein, said insert being positioned in the longitudinal main section of the frame member and opening outwardly, means on the frame member to securely hold the insert in position, inwardly opening channelled insert positioned in the legs of the frame member, the upper walls of said inserts being adapted to be pressed downwardly to tightly grip the side edges of the covering material. 100

5. In a handbag, a frame member having a longitudinal main section and channelled, right angularly directed legs to present sub- 115

120

135

stantially the shape of an inverted **U**, the channels of the legs opening outwardly and laterally relative to the bag, means for securing the bag covering material to the longitudinal, main section of the frame member, and inwardly opening channelled inserts positioned in the legs of the frame member, the upper walls of said inserts being adapted to be pressed downwardly to tightly grip the side edges of the covering material.

This specification signed this 14th day of June, 1932.

WILLIAM C. HIERING.
